THE NORRIS PETERS CO., WASHINGTON, D. C.

UNITED STATES PATENT OFFICE.

FRANK M. THORPE, OF LAMAR, MISSOURI.

BAG-HOLDER.

No. 832,638.

Specification of Letters Patent.

Patented Oct. 9, 1906.

Application filed October 31, 1905. Serial No. 285,360.

To all whom it may concern:

Be it known that I, FRANK M. THORPE, a citizen of the United States, residing at Lamar, in the county of Barton and State of Missouri, have invented certain new and useful Improvements in Bag-Holders, of which the following is a specification.

This invention relates to bag-holders; and my object is to produce a device of this character which can be easily and conveniently charged with paper or other bags and from which said bags may be readily removed either individually or collectively, but from which they cannot be accidentally dislodged.

A further object is to produce a bag-holder of this character of simple, strong, durable, cheap, and compact construction.

To these ends the invention consists in certain novel and peculiar features of construction and organization, as hereinafter described and claimed, and in order that it may be fully understood reference is to be had to the accompanying drawings, in which—

Figure 1 is a side elevation of a bag-holder embodying my invention, the same being charged with bags of different sizes. Fig. 2 is a front view of the same. Fig. 3 is a rear view with the bags omitted.

In the said drawings a hanger-piece is preferably formed of a short piece of heavy wire bent to produce the loop or eye 1 and the horizontal arms 2, projecting oppositely from said loop or eye and terminating in hook ends 3. A series of frames (four in this instance) of different lengths and widths are each formed of a piece of wire of proper gage. The frames respectively comprise a pair of arms 4, 4^a, 4^b, and 4^c, which by preference and for the sake of compactness converge upward slightly and terminate in hooks or eyes 5, 5^a, 5^b, and 5^c, respectively, engaging the arms 2, on which they are pivoted or hinged, the arms 4 and hooks of said frames occupying substantially the positions shown clearly in the drawings. Near their lower ends the arms are bent to form the coils 6, 6^a, 6^b, and 6^c, and at their extreme lower ends said arms are bent to form the forwardly-projecting shelf portions 7, 7^a, 7^b, and 7^c and terminate in the integral cross connections or arches 8, 8^a, 8^b, and 8^c. When viewed from the front or rear, the arms of said frames are substantially parallel with each other.

Carried by the largest frame, which is the rearmost one, is a guard for preventing lateral displacement of the bags, said guard-

frame being composed of wire bent to form a cross-piece 9, extending through the coils 6. At the ends of the cross-piece the wire is bent to form the forwardly-projecting arms 10, which in turn are bent back upon themselves to provide rearwardly-projecting arms 11 at the outer sides of arms 10. At the rear ends of arms 11 the wire is bent upwardly to form the arms 12, and said arms 12 terminate at 65 the upper ends in forwardly and inwardly projecting eyes 13. The guard-frame carried by the second largest frame depending from arms 2 is somewhat narrower than the first-named guard-frame and consists of a 70 piece of wire bent to form the cross-piece 14, extending through the coils of the last-named depending frame, and forwardly-projecting arms 15 at the ends of said cross-piece. At the front ends of said arms 15 the wire is 75 bent back upon itself to form the rearwardly-projecting arms 16, and from the rear ends of said arms 15 said wire is bent to form the depending arms 17, terminating in outwardly and rearwardly projecting eyes 18, slidingly 80 engaging arms 12 of the guard-frame immediately below, said arms 17 also extending slidingly through the eyes 13 of the first-named guard-frame. The guard-frame comprising parts 14^a, 15^a, 16^a, 17^a, and 18^a of the third 85 largest frame depending from arms 2 is of precisely the same construction as the second one, except that its eyes 18^a project forwardly and outwardly instead of rearwardly and outwardly, as in the second largest guard-frame. 90 It is by preference somewhat narrower than the guard-frames before described, and its arms 17^a are preferably longer, because the corresponding arms of the second largest frame project downward, whereas the arms 95 12 of the lower guard-frame project upward. Its eyes 18^a slidingly engage the arms 17 above the engagement with said arms of eyes 13 of the first-named guard-frame. The guard-frame comprising parts 14^b, 15^b, 16^b, 100 17^b, and 18^b of the fourth or smallest frame depending from arms 2 is precisely the same as the third guard-frame and has its eyes 18^b engaging the arms 17^a of such guard-frame.

From the description of the parts thus far 105 it will be apparent that by grasping the shelf portion of one of the depending frames and pulling it forward said frame will swing forward, together with all of the corresponding frames in front of it, and therefore increase 110 the space between the frame grasped and the frame immediately behind it. This

widening of the space between the frame and the one immediately behind it enables the operator to slip a large package of bags into said space, the rear side of said package bearing against the arms 4 of said rear frame. Said package also fits between the forwardly-projecting arms of the guard-frame carried by said rear frame and rests at its lower end upon the shelf-arms of said rear frame, the 10 arched cross-piece at the front ends of said shelf-arms bearing against the front side of said package. The same manipulation will enable the operator to withdraw the said bags collectively. To hold the hinged hanger-frames yieldingly from forward movement, and therefore guard against accidental dislodgment of the bags from said holder, a spring-clamp is employed to press against the topmost package of bags. To produce 15 this clamp, a piece of spring-wire is bent to form the depending U-shaped clamp-arm 19, mounted at its upper end upon the arms 2, as at 20, the ends of the wire depending from said arms and terminating in hooks 21 for engagement, by preference, with one or more of the arms 4, 4^a, 4^b, and 4^c of the hanger-frames, the terminals of the hook being at the front side, by preference, of said hanger-frames. When each hanger-frame is equipped with a 25 package of proper-sized bags, the salesman or other person desiring one of any particular size can grasp the same near its lower portion and pull it toward him, the result being said bag is drawn out of the holder without disturbing the others, it being apparent that the pressure of the clamp alone is what holds the topmost series of bags in place. In fact, the pressure of the clamp is necessary to hold 30 all of the sets of bags reliably, for the reason that the peculiar connection between the guard-frames is such that the friction engendered overcomes the gravitational tendency of the hinged hanger-frames. A holder of this character can be easily and quickly 35 hooked upon or removed from a nail or other support and is peculiarly adapted for use by confectionery or fruit venders or for outside stands. Upon such stands, as a rule, space is limited, and the ordinary pedestal-holders of 40 the character disclosed in Patent No. 767,022, issued to me August 9, 1904, cannot be conveniently used.

From the above description it will be apparent that I have produced a hanging bag-holder embodying the features of advantage enumerated as desirable.

Having thus described the invention, what I claim as new, and desire to secure by Letters Patent, is—

60 1. A bag-holder, comprising a support, a series of hanger-frames depending from said support and provided at their lower ends with forwardly-projecting shelves, and guard-frames carried by each of the depending frames; each guard-frame below the top one

having a sliding connection with the guard-frame above it.

2. A bag-holder, comprising a support, a series of hanger-frames depending from said support and provided at their lower ends 70 with forwardly-projecting shelves, guard-frames carried by each of the depending frames, and a clamp for engagement with the package of bags carried by the topmost hanger-frame, to hold said frames pressed 75 yieldingly together.

3. A bag-holder, comprising a support, a series of hanger-frames depending from said support and provided at their lower ends 80 with forwardly-projecting shelves, and guard-frames carried by and hinged to the hanger-frames; each guard-frame below the top one having a sliding connection with the guard-frame above it.

4. A bag-holder, comprising a support, a 85 series of hanger-frames depending from said support and provided at their lower ends with forwardly-projecting shelves, guard-frames carried by and hinged to the hanger-frames, and a clamp for engagement with 90 the package of bags carried by the topmost hanger-frame, to hold said frames pressed yieldingly together.

5. A bag-holder, comprising a support, a series of hanger-frames depending from said 95 support and provided with forwardly-projecting shelves at their lower end, said shelves having upwardly-projecting portions at their front ends, and guard-frames carried by each of the depending or hanger frames; each 100 guard-frame below the top one having a sliding connection with the guard-frame above it.

6. A bag-holder, comprising a cross-piece adapted to be suspended from a suitable support, a series of hanger-frames depending 105 from said cross-piece, any one of which except the bottom or rear one is adapted for movement at its lower end forwardly from the hanger-frame immediately to the rear, and guard-frames hinged to each hanger-frame, each guard-frame above the bottom one being slidingly connected to the hanger-frame below it.

7. A bag-holder, comprising a cross-piece adapted to be suspended from a suitable 115 support, a series of hanger-frames depending from said cross-piece, any one of which except the bottom or rear one is adapted for movement at its lower end forwardly from the hanger-frame immediately to the rear, 120 guard-frames hinged to each hanger-frame, each guard-frame above the bottom one being slidingly connected to the hanger-frame below it, and a spring-clamp carried by said cross-piece and adapted to press rearwardly 125 against the topmost package of bags carried by the holder.

8. In a bag-holder, a hanger-frame provided with a forwardly-projecting shelf at its lower end, and a guard-frame consisting of a 130

cross-piece hinged to the said hanger-frame, and provided at its ends with forwardly-projecting arms.

9. In a bag-holder, a hanger-frame provided with a forwardly-projecting shelf at its lower end, a guard-frame consisting of a cross-piece hinged or pivoted to said hanger-frame and provided at its ends with forwardly-projecting arms, a second hanger-frame provided with a forwardly-projecting shelf above the shelf of the first-named

hanger-frame, a guard-frame hinged or pivoted to the second hanger-frame, and provided at its ends with forwardly-projecting arms, and a loose slideable connection between the arms of said guard-frames. 15

In testimony whereof I affix my signature in the presence of two witnesses.

FRANK M. THORPE.
